(57) **CLAIM**

The ornamental design for a sport bottle cap, as shown and described.

DESCRIPTION

FIG. 1 is a perspective view of the sport bottle cap with the cover in the closed position;

FIG. 2 is a perspective view of the sport bottle cap with the cover in the open position;

FIG. 3 is a front view thereof, with the cover in the closed position;

FIG. 4 is a side view thereof, with the cover in the closed position;

FIG. 5 is a back view thereof, with the cover in the closed position;

FIG. 6 is a front view thereof, with the cover in the open position;

FIG. 7 is a side view thereof, with the cover in the open position;

FIG. 8 is a back view thereof, with the cover in the open position;

FIG. 9 is a top plan view thereof, with the cover in the closed position;

FIG. 10 is a top plan view thereof, with the cover in the open position; and,

FIG. 11 is a perspective view of the sports bottle cap shown in condition of use.

The broken lines illustrate portions of the sports bottle cap and environmental structure which form no part of the claimed design.
